DESIGN FOR A HAIRBRUSH

Lewis H. Gustafson, Northampton, Mass., assignor to Pro-phy-lac-tie Brush Company, Northampton, Mass., a corporation of Delaware

Application January 17, 1940, Serial No. 89,526

Term of patent 7 years

To all whom it may concern:

Be it known that I, Lewis H. Gustafson, a citizen of the United States of America and a resident of Northampton, in the county of Hampshire, Commonwealth of Massachusetts, have invented a new, original, and ornamental Design for Hairbrushes, of which the following is a specification, reference being had to the accompanying drawing, forming part thereof.

In the drawing:

Fig. 1 is a top or back view of a hairbrush showing my new design,

Fig. 2 is a side view thereof,
Fig. 3 is a face view with the bristles in section,
and

Figs. 4 and 5 are sections on the line 4—4 and 5—5 respectively, Fig. 1.

I claim:

The ornamental design for a hairbrush, substantially as shown.

LEWIS H. GUSTAFSON.
